[57] CLAIM

The ornamental design for a thermometer-clock face, as shown and described.

DESCRIPTION

FIG. 1 is a front elevation view of a thermometer-clock face showing my new design;

FIG. 2 is a right side elevation view thereof, the left side being a mirror image thereof;

FIG. 3 is a top view thereof, the bottom being substantially a mirror image thereof;

FIG. 4 is a rear elevation view thereof; and,

FIG. 5 is a front perspective view thereof.

The broken line showing of hands are for illustrative purposes only and form no part of the claimed design.

FIG. 1

FIG. 2

FIG. 3

FIG. 4

FIG. 5
